SPRAY OIL MISCELLY SULPHONATED COMPOUND

Frank F. Lindstaedt, Oakland, Calif.

No Drawing. Application March 12, 1934,
Serial No. 715,179

19 Claims. (Cl. 167—28)

As is well known, sulphonated oils provide an effective emulsifying agent for mixing petroleum distillates with water. Due, however, to the comparative insolubility of the sulphonated oils in the oil phase, heretofore in order to cause enough of the sulphonated oil to dissolve or mix with the petroleum oil to provide the desired emulsification between the phases, an excessive amount of cresylic acid was combined with the sulphonated oil to make the latter soluble in the spray oil. Particularly was this true in the provision of so-called self-emulsifying type of spray oils. In this form, the emulsifying agent is combined with the petroleum oil or other internal phase before the latter is mixed with the water or other continuing phase, the emulsifier being usually dissolved, dispersed or held in colloidal state in the internal phase so that while the product may be shipped or stored practically indefinitely, it will on being merely mixed and agitated with the water form a complete emulsion suitable for spraying. An indication of the difficulty of rendering the sulphonated oil soluble or dispersible in the petroleum oil by previous methods may be gained from the fact that the amount of cresylic acid used for the purpose was from five to ten times the amount of sulphonated oil dissolved. Furthermore, owing to the presence of so much cresylic acid in proportion to the sulphonated oil, the activity of the latter was so far curtailed that in order to provide for the proper emulsion of the oil and water phases, the amount of the cresylic acid and sulphonated oil mixture required to be added to the oil phase represented as high as 20% of the self-emulsifying product. In contrast with the foregoing, I arrange for the thorough emulsification by the incorporation in the oil phase an amount of sulphonated oil representing but less than five per cent of said product. As a matter of fact from $\frac{1}{2}$ to $1\frac{1}{2}\%$ of the sulphonated oil is sufficient for most commercial purposes. It is to be noted therefore that not only is the cost of the product appreciably reduced, but there will be no large amounts of cresylic acid, salts, or other substances in the product which may be injurious to the plants or vegetation on which it is sprayed.

In accordance with the foregoing, it is an object of my invention to combine the sulphonated oil with some substance which will render same readily soluble or dispersible in the petroleum oil, which will not be injurious to the plant—at least in so far as the amount required to be used with the oil, and which will of itself be readily soluble or dispersible in the oil phase to provide, in

addition to the sulphonated oil, an emulsifier medium.

Another object of the invention is to provide a compound of the character described in which the substance arranged to be combined with the sulphonated oil may be any one of a wide variety, is usable in acid or ester form, is readily and easily procurable, and lends itself to ready compounding with the sulphonated oil.

A further object of the invention is to combine the sulphonated oil with a substance which will make possible the production of an emulsion, quick breaking but sufficiently stable to insure the necessary carrying of the oil phase to the plant during the spraying operation.

The invention possesses other objects which with the foregoing will be set forth in the following description of the preferred forms of the invention. It is to be understood, however, that I do not limit myself to said description, as I may adopt variations from said forms within the scope of the invention as set forth in the claims.

Stated in a general way, I have found that by heat treating a sulphonic acid or a sulphonated oil with an ordinary fatty acid or its ester derivatives which as is known are in contrast to the sulphonic substances generally readily soluble in petroleum distillates of a wide range of fractions and viscosities. Particularly is my discovery applicable for rendering soluble in the oil phase the sulphonates of the fatty acids.

The invention may be more readily understood by illustration of a specific embodiment. For example, I take equal parts by weight of sulphonated castor oil and coconut acid oil and heat them together at a temperature of between 100 to 125 degrees centigrade for from one to four hours and under constant agitation. The product is then allowed to settle for from six to twenty-four hours, whereupon the clear supernatant liquid is decanted and may be added directly to the petroleum oil as an effective "internal emulsifier." For a commercial dormant spray the use of $1\frac{1}{2}$ parts of internal emulsifier with $98\frac{1}{2}$ parts of 80 to 120 viscosity petroleum oil will provide a self-emulsifying oil which when mixed with the water phase will have the necessary carrying qualities but will be sufficiently quick breaking to insure adherence of the oil to the plane surface.

It will be noted that in the example of the emulsifier compound above given, both the sulphonate and the unsulphonated substance with which it is combined and treated, are fatty acid derivatives, and as before stated, I have found

that almost any combination of a sulphonated fatty acid and a fatty acid or oil will when treated together as above, provide an emulsifier compound readily soluble or colloidally dispersible in the petroleum oil phase. While the exact reason why the sulphonated oil is rendered so readily soluble in the oil phase, due to the treatment with the fatty acids or oils, is not understood, it is believed that due to such treatment some of the higher sulphonated groups of the sulphonated oil—that is to say the less stable sulphonated components—are transferred to the acid oil or other oil to produce low sulphonated bodies in the added oil. The sulphonated oil originally had such a high percentage of sulphonated bodies that it was not completely oil soluble but due to the splitting off of the less firmly bound sulphonated groups and their subsequent transfer to the added oil, the product after settling or filtering becomes completely soluble in hydrocarbon, fish, or other spray oil in all proportions.

Experience has shown that the unsaturated oils and fatty acids are more effective in producing completely oil soluble emulsifiers. For instance, in the case of sulphonated castor oil and cocoanut oil I find that from four to six hours of heating at 125 degrees C. is necessary (plus settling or filtering), whereas with sulphonated castor oil and fish oil only about one half hour of heating at 125 degrees C. is necessary to produce a completely oil soluble compound. In the latter case no settling or filtering is necessary.

My tests have also disclosed that it is possible to combine for the purpose of forming the emulsifier compound, practically any sulphonated fatty acid or oil with any fatty acid or its derivatives such as usually found in animal or vegetable matter. As a matter of fact, it is practical to combine a sulphonated oil of one fatty acid with an unsulphonated fatty acid of the same kind. However, I prefer to make combinations with different fatty acids or their derivatives, and the following are examples of some of the combinations found very effective when heated and treated as explained in connection with the first described example:

	Parts
Sulphonated oleic acid	1
Naphthenic acid	1
Sulphonated olive oil	1
Corn oil	1

Furthermore, if desired, more than one kind of sulphonated acid or oil may be used with one or more kinds of fatty acids or oils, as will be clear from the following example:

	Parts
Sulphonated castor oil	2
Naphthenic acid	1
Corn oil	1

It will be evident from the foregoing explanation that the acids, salts, esters and oils or other derivatives of the substances combined in the emulsifier compound, may in general be used interchangeably as the circumstances and conditions warrant.

I claim:

1. A method of rendering miscible in a hydrocarbon spray oil a sulphonated fatty acid, which comprises mixing said sulphonated acid with a fatty acid, subjecting the mixture to a temperature of about 100 to 125 degrees centigrade for about from one to four hours and keeping same agitated during such heating action.

2. A method of making an internal emulsifier for a hydrocarbon spray oil from a sulphonated fatty acid, normally substantially immiscible in the spray oil, which comprises mixing an oil miscible fatty acid with said sulphonated acid, subjecting the mixture to agitation and heat of a temperature of about 100 to 125 degrees centigrade for about from one to four hours, and then separating the clear liquid from the mixture after the latter has been allowed to settle from approximately six to twenty-four hours. 10

3. A method of forming a hydrocarbon spray oil internal emulsifier which comprises mixing a substance from the group consisting of sulphonated fatty oils and sulphonated fatty acids with a substance from the group consisting of fatty oils, fatty acids and naphthenic acids and heating to a temperature sufficient to produce a liquid which will be substantially entirely miscible in the spray oil. 15 20

4. A method of forming a hydrocarbon spray oil internal emulsifier which comprises mixing a sulphonated fatty acid and a substance from the group consisting of fatty oils, fatty acids and naphthenic acids, and heating to a temperature 25 sufficient to produce a liquid which will be substantially entirely miscible in the spray oil.

5. A method of forming a hydrocarbon spray oil internal emulsifier which comprises mixing a substance from the group consisting of sulphonated fatty oils and sulphonated fatty acids with naphthenic acid, and heating to a temperature 30 sufficient to produce a liquid which will be substantially entirely miscible in the spray oil. 30

6. A method of forming a hydrocarbon spray oil internal emulsifier which comprises mixing a substance from the group consisting of sulphonated fatty oils and sulphonated fatty acids with cocoanut oil, and heating to a temperature sufficient to produce a liquid which will be substantially 40 entirely miscible in the spray oil. 40

7. A method of forming a hydrocarbon spray oil internal emulsifier which comprises mixing a substance from the group consisting of sulphonated fatty oils and sulphonated fatty acids with fish oil, and heating to a temperature sufficient to produce a liquid which will be substantially 45 entirely miscible in the spray oil. 45

8. A method of forming a hydrocarbon spray oil internal emulsifier which comprises mixing sulphonated oleic acid with a substance from the group consisting of fatty oils, fatty acids and naphthenic acids, and heating to a temperature sufficient to produce a liquid which will be substantially 50 entirely miscible in the spray oil. 55

9. A method of forming a hydrocarbon spray oil internal emulsifier which comprises mixing sulphonated oleic acid with naphthenic acid, and heating to a temperature sufficient to produce a liquid which will be substantially entirely miscible 60 in the spray oil. 60

10. A method of forming a hydrocarbon spray oil internal emulsifier which comprises mixing sulphonated castor oil with cocoanut oil, and heating to a temperature sufficient to produce a liquid which will be substantially entirely miscible in the spray oil. 65

11. A method of forming a hydrocarbon spray oil internal emulsifier which comprises mixing sulphonated castor oil with fish oil, and heating to a temperature sufficient to produce a liquid which will be substantially entirely miscible in the spray oil. 70

12. A self-emulsifying horticultural spray oil adapted when mixed with water to provide a 75

- semi-stable emulsion capable of quickly breaking on being sprayed, comprising a hydrocarbon spray oil, and an internal emulsifier including a product derived from the interaction of a mixture of a substance from the group consisting of sulphonated fatty oils and sulphonated fatty acids with a substance from the group consisting of fatty oils, fatty acids and naphthenic acids which have been heated to a temperature sufficient to produce a liquid which will be substantially entirely miscible in the spray oil.
13. A self-emulsifying horticultural spray oil adapted when mixed with water to provide a semi-stable emulsion capable of quickly breaking on being sprayed, comprising a hydrocarbon spray oil, and an internal emulsifier including a product derived from the interaction of sulphonated oleic acid with a substance from the group consisting of fatty oils, fatty acids, and naphthenic acids, which have been heated to a temperature sufficient to produce a liquid which will be substantially entirely miscible in the spray oil.
14. A self-emulsifying horticultural spray oil adapted when mixed with water to provide a semi-stable emulsion capable of quickly breaking on being sprayed, comprising a hydrocarbon spray oil, and an internal emulsifier including a product derived from the interaction of a substance from the group, consisting of sulphonated fatty oils and sulphonated fatty acids with naphthenic acids which have been heated to a temperature sufficient to produce a liquid which will be substantially entirely miscible in the spray oil.
15. A self-emulsifying horticultural spray oil adapted when mixed with water to provide a semi-stable emulsion capable of quickly breaking on being sprayed, comprising a hydrocarbon spray oil, and an internal emulsifier including a product derived from the interaction of a substance from the group consisting of sulphonated fatty oils and sulphonated fatty acids with cocoanut oil which have been heated to a temperature sufficient to produce a liquid which will be substantially entirely miscible in the spray oil.
16. A self-emulsifying horticultural spray oil adapted when mixed with water to provide a semi-stable emulsion capable of quickly breaking on being sprayed, comprising a hydrocarbon spray oil, and an internal emulsifier including a product derived from the interaction of a substance from the group consisting of sulphonated fatty oils and sulphonated fatty acids with fish oil, which have been heated to a temperature sufficient to produce a liquid which will be substantially entirely miscible in the spray oil.
17. A self-emulsifying horticultural spray oil adapted when mixed with water to provide a semi-stable emulsion capable of quickly breaking on being sprayed, comprising a hydrocarbon spray oil, and an internal emulsifier including a product derived from the interaction of a mixture of sulphonated castor oil with cocoanut oil which have been heated to a temperature sufficient to produce a liquid which will be entirely miscible in the spray oil.
18. A self-emulsifying horticultural spray oil adapted when mixed with water to provide a semi-stable emulsion capable of quickly breaking on being sprayed, comprising a hydrocarbon spray oil, and an internal emulsifier including a product derived from the interaction of a mixture of sulphonated oleic acid with naphthenic acid which have been heated to a temperature sufficient to produce a liquid which will be entirely miscible in the spray oil.
19. A self-emulsifying horticultural spray oil adapted when mixed with water to provide a semi-stable emulsion capable of quickly breaking on being sprayed, comprising a hydrocarbon spray oil, and an internal emulsifier including a product derived from the interaction of a mixture of sulphonated castor oil with fish oil which have been heated to a temperature sufficient to produce a liquid which will be entirely miscible in the spray oil.

FRANK F. LINDSTAEDT.
